UNITED STATES PATENT OFFICE.

CHARLES N. FORREST, OF RAHWAY, NEW JERSEY, ASSIGNOR TO THE BARBER ASPHALT COMPANY, OF PHILADELPHIA, PENNSYLVANIA, A CORPORATION OF WEST VIRGINIA.

GAME COURT.

Application filed September 23, 1925. Serial No. 58,023.

My invention relates to game courts, for tennis, squash, hand ball, and the like. Such courts should have a hard, clean surface, and require markings to indicate the areas of play. Grass and "skin" courts, however, entail constant attention and expense to maintain them in satisfactory condition, owing both to the effects of weather and the growth of grass or weeds. Moreover, the lime markings usually employed for them are defaced by rain and by the shoes of the players, and must be frequently renewed.

I aim to obviate such drawbacks, and to provide an improved court with a hard, smooth, durable surface and practically eradicable markings. How these and other advantages can be realized through my invention will appear from the description hereinafter of a selected and preferred embodiment thereof.

In the drawings, Fig. I, is a plan view of a tennis court and,

Fig. II, shows a vertical section through the court and its foundations, taken on the line II—II in Fig. I.

In constructing a court according to my invention, the first step, assuming that a suitably drained sub-base of soil has already been prepared, is to lay down a base or foundation 4 of hydraulic cement or concrete. The construction of such foundations is well understood by those familiar with the laying of concrete sidewalks and concrete roads and road foundations, so that a detailed description is necessary. For my purposes, the base 4 is constructed or provided with concrete or cement elevations 5 adapted to form the required markings of the finished court, exemplified in the drawings by the narrow curb-like lines enclosing the total area of the court and defining its alleys and other subdivisions 6. The areas 6 amongst the raised markings 5 are recessed or depressed below the markings 5 to a depth of about an inch. For a tennis court, the raised markings 5 will appear in plan as ribbon-like strips about two inches wide. Whatever the form of the markings 5, their top surfaces are preferably finished

as smooth as possible; like the finest concrete paving or floors. For reasons which will appear hereinafter, the markings 5 may even be constructed or surfaced with white portland cement, instead of with the grey cement that will naturally be used for the rest of the base 4.

After the base 4 is set and properly *cured*, I fill in the depressed areas 6 with bituminous mastic 7, bringing its finished top surface flush or level with the top surface of the concrete or cement markings 5. Preferably, I lay the bituminous mastic 7 in two courses, the first, 8, comprising an aggregate of one-quarter inch crushed stone or gravel and sand, and the second, 9, comprising sand and mineral dust as its aggregate. The aggregates for these courses 8, 9 may be mixed and coated either with hot, molten bituminous cement, or with cold bituminous cement emulsion. The first course 8 may be laid to a depth of about one-half inch to three-quarter inch; and after it has been spread and well compacted, the second course will be laid and finished to a sufficient depth to bring the mastic areas 7 flush with the concrete markings 5 already described. Care should be taken to spread the mastic of both courses 8, 9 to a uniform depth, to compress it into the depressions or recess 6, and to work it to a smooth, even surface, flush and level with the markings 5. When the mastic filling has set well (by cooling, in the case of hot mix, or by evaporation in the case of cold mix), the court is ready for use.

Such a court is not only durable and most permanently marked, so as never to need liming or the like, but presents a general playing surface 7 which is substantially black in color except for the strongly contrasted white or grayish concrete markings 5. The contrast is, of course, heightened by making or surfacing the concrete or cement mixture for the markings 5 with white hydraulic cement, as already mentioned. The black surface of the court does not reflect sunlight, and is therefore much easier on the eyes than a light colored "skin" court: also, a whitish or greyish tennis ball

is more sharply visible on it. In its entirety, the surface of the court is thoroughly water-proof and weather resistant.

Having thus described my invention, I

5 claim:—

A permanently-marked game court comprising a cement-concrete base embodying upstanding ribs defining the required markings and forming enclosures entirely sur-

rounded by said ribs, and bituminous mastic 10 filling said enclosures with its upper surface substantially level with the top of the ribs.

In testimony whereof, I have hereunto signed my name at Maurer, N. J., this 17th 15 day of September, 1925.

CHARLES N. FORREST.
